FIG. 4.

James J. Funsten ^{Inventor}
By Strong & Townsend ^{Attorneys}

UNITED STATES PATENT OFFICE.

JAMES J. FUNSTEN, OF SAN FRANCISCO, CALIFORNIA.

HOLLOW INTERBONDING BRICK AND CONSTRUCTION.

1,318,140.

Specification of Letters Patent.

Patented Oct. 7, 1919.

Application filed August 28, 1915. Serial No. 47,831.

To all whom it may concern:

Be it known that I, JAMES J. FUNSTEN, a citizen of the United States, residing at San Francisco, in the county of San Francisco 5 and State of California, have invented a certain new and useful Hollow Interbonding Brick and Construction, of which the following is a full, clear, and exact description, reference being made to the accompanying drawings.

My invention relates to an interbonding hollow building brick and structures composed of such brick, and to a means of uniting such brick so as to make a strong 15 integral structure. It also enables the brick to be laid in the wall so that the structure is completed with one given width and form of brick in a single continuous operation. It further consists in a novel construction 20 of grooved brick, which are shaped to engage with each other in positions so related that with a suitable cement they may be united to form strong integral structures.

The invention includes details of construction, which will be more fully explained by reference to the accompanying drawings in which,—

Figure 1 is a perspective view of a brick constructed in accordance with the present 30 invention;

Fig. 2 is a similar view of a modified form of brick embodied in a wall construction: and

Figs. 3 and 4 are perspective views of 35 walls constructed with the type of brick depicted in Fig. 1.

As shown in the drawings, "A" represents the face and back of the brick; "B" represents the interior walls of the tile; "C" 40 represents the bottom walls of the brick and "D" represents the top wall of the brick. The cement receiving channels are represented by the number 1. The hollow channels are represented by the number 2. The 45 block, in its simplest form, therefore, comprises spaced U-shaped members arranged side by side and having their inner arms connected at their upper edges by a bridge.

Fig. 1 shows the construction of the brick. 50 Fig. 2 shows additional air and cement receiving channels when desired for additional width and strength.

Fig. 3 is a perspective view showing these 55 bricks superposed and shows how the walls "A" are placed one over the other in different courses to form the face and back of the

wall. The walls "B" also are placed in vertical alinement. The wall "D" which forms the top of the brick and connects the cement receiving channels, number 1, prevents the 60 mortar or other material from running into and closing the hollow channels number 2; Fig. 3 shows how the cement receiving channels number 1 are placed one upon the other in different courses and separated by the bottom wall "C."

In structures consisting of walls or their equivalents and supplemental surfacing, various methods have been employed to secure such structural elements together. In this 70 invention, I unite and combine all structural and facing units for any given thickness of wall into one brick without the use of connecting rods or other extraneous means.

This brick may be made of any suitable 75 material, and when manufactured of clay it will be obvious that any variety may be used to produce any desired color, texture or finish. The face may be vitrified, glazed, corrugated, plain or roughened to give a 80 rustic effect to the finished wall. The surfaces of the brick may be scored wherever desired for the better bonding of the mortar or adhesion of the plaster, which when used may be applied directly to the surface of the 85 brick without the necessity for the use of furring or waterproofing.

While not limiting this brick to size, it will be obvious that in width it will be made to conform to the accepted requirements of 90 given thickness for walls, and of such a height and length as to conform to the usual and accepted building brick sizes and proportions in height and length, as in the completed wall they will have the same appearance.

These brick when laid in the wall are much stronger for relative weight in resisting all strains that may be applied than usual brick construction, due to their shape 100 and the manner in which they are laid. Another advantage of walls built of my brick is their non-conductivity of the elements due to the insulation afforded by the air spaces contained in the channels in the 105 interior of the wall, which are occasioned by the construction of the brick and are kept free from the entrance of mortar or other material when the brick are being laid.

The mortar joints are broken vertically 110 and extend in a continuous parallel direction.

The brick are shown as hollow for lightness and formed with a minimum of material required to obtain necessary strength. Great strength and rigidity are obtained by 5 the manner in which the brick are used. The size may be so governed that any desired thickness of wall may be combined in one brick, thereby eliminating several operations in manufacture and construction, and 10 are designed to produce the desired structure with the walls and webs alining when united with similar brick.

My brick may be manufactured, due to 15 their simplicity of design and lightness of weight, very economically, also due to their size, shape, light weight and the manner in which they are laid, the labor cost of constructing is reduced.

The brick are preferably so laid with 20 reference to each other that each overlap, thus breaking all vertical joints and permitting any bond or pattern work to be employed.

Having thus described my invention, what 25 I claim and desire to secure by Letters Patent is,—

1. A hollow tile brick comprising, in its

entirety, similar spaced U-shaped members of uniform width and depth arranged side by side, and a U-shaped bridge having lateral 30 wings integrally connecting the adjacent inner walls of the U-shaped members at their upper edges to provide a pair of similar downwardly facing spaces, the thickness of the walls of the U-shaped members and 35 bridge being uniform throughout.

2. A hollow tile brick comprising, in its entirety, similar spaced U-shaped members of uniform width and depth arranged side by side and constituting twin walled mortar 40 receiving channels of substantial width, and a horizontal bridge integrally connecting the adjacent inner walls of the U-shaped members at their upper edges to provide a downwardly facing channel, forming an air 45 space, the thickness of the walls of the U-shaped members and bridge being uniform throughout.

In testimony whereof, I hereunto affix my signature in the presence of two witnesses. 50

JAMES J. FUNSTEN.
